United States Patent Office

Des. 190,847
Patented July 4, 1961

190,847

TEXTILE FABRIC OR SIMILAR ARTICLE

Sergei Bogdanovich, Carmel, N.Y., assignor to Weil & Durrse, Inc., New York, N.Y., a corporation of New York

Filed Aug. 24, 1960, Ser. No. 61,878

Term of patent 3½ years

(Cl. D92—1)

Fig. 1

Fig. 2

FIGURE 1 is a face view of a textile fabric or similar article, showing my new design. The full width of the fabric is disclosed, horizontally, and the design unit is repeated vertically as indicated by the broken lines.

I claim:

The ornamental design for a textile fabric or similar article, substantially as shown and described.
